UNITED STATES PATENT OFFICE.

JAMES M. BAXTER AND THOMAS H. SIKES, OF GREENSBORO, NORTH CAROLINA.

TRACK-WRENCH.

1,184,711.

Specification of Letters Patent.

Patented May 30, 1916.

Application filed September 7, 1915. Serial No. 49,304.

To all whom it may concern:

Be it known that we, JAMES M. BAXTER and THOMAS H. SIKES, citizens of the United States, residing at Greensboro, in the county of Guilford and State of North Carolina, have invented a new and useful Track-Wrench of which the following is a specification.

This invention relates to improvements in track wrenches, and more particularly to that class known as double-acting ratchet wrenches, wherein the ratchet pawl may be readily thrown into position to actuate the nut in either a right or a left hand direction, 15 as desired.

One object of the present invention is to provide a wrench having a nut receiving socket sufficiently offset from the adjacent face of the operating handle to permit of 20 its ready application to the nuts of rail joints or the like to allow of the unscrewing of the nut, and at the same time the oscillatory movement of the wrench stock will not be interfered with by the adjacent side 25 face of the head of the rail.

Another object is the provision of an inter-changeable rotary nut actuating head or hub which may be readily removed from the wrench and another applied to the device having a larger or a smaller nut socket as desired, by the simple manipulation of a set screw.

A further object is the provision of a dog or pawl which may be turned around to present new points or teeth to the ratchet wheel after one set has become worn, and will still be capable of either right or left hand actuation of the nut turning head or hub.

A full and complete understanding of the 40 invention may be obtained from a careful consideration of the following detailed description, taken in connection with the accompanying drawing forming a part of this specification; it being understood that while 45 the drawing shows a practical form of the invention, the latter is not confined to strict conformity therewith, but may be changed or modified, as long as such changes or modifications mark no material departure 50 from the salient features of the invention, as specifically pointed out in the claims hereto appended.

In the drawing, in which like reference 55 characters designate like parts in each of the several figures:—Figure 1 is a perspective view of our improved wrench; Fig. 2 is an enlarged face view of the active end

thereof; Fig. 3 is a longitudinal section on the line 3—3 of Fig. 2; Fig. 4 is a section on the line 4—4 of Fig. 2; and Fig. 5 is a 60 face view of the rear side of the double acting pawl or dog.

The usual tapering handle or stock 1 is employed, which may be of a length sufficient to enable the operator to apply the active 65 end of the wrench to a nut to be removed from a rail or the like, and still enable the operator to actuate the same while in a standing position. The larger end of the stock is transversely bored as at 2 to form a 70 bearing for the rotating head or socket piece 3, which is provided with a lateral projecting bearing portion 4 adapted to enter the bore 2 and to be retained therein by a detachable collar 5, made fast to the extremity of the extension 4 by a set screw 6, the 75 said extension 4 being sufficiently long to pass through and beyond the rear face of the stock 1 and there to receive the collar 5.

On the face of the rotating head opposite 80 to the extension 4 is provided a rectangular socket 7 which is adapted to receive the nut to be removed or applied. It will be seen that the head 3 may, by the removal of the detachable collar 5, be readily removed from 85 the stock 1 and a similar head having a larger or a smaller rectangular socket 7, be substituted, thus adapting the device for use upon different sizes of nuts.

The length of the head from the adjacent 90 face of the stock 1 to that face thereof having the socket 7 therein is sufficient to space the actuating stock 1, sufficiently from the ball of a rail to prevent any interference 95 thereby in the oscillatory movement of the 100 said stock. The outer surface of the head 3 is preferably tapered and is provided at its largest diameter with a series of double faced ratchet teeth 8 which are adapted to be engaged by a pawl, to be hereinafter described, and to be rotated in either a right or a left hand direction to apply a nut to a bolt or remove the same therefrom. The head 3 is further provided with a central longitudinal bore 9 extending from the rectangular socket 7 to the rear face of the extension 4 and is adapted to receive the extended ends of bolts where they may be found projecting some distance beyond the 105 face of the nut.

Located upon the stock 1 on the same side with the ratchet teeth 8 and adjacent thereto, is a four pointed double acting reversible pawl 10 mounted for swinging

movement upon a bolt 11 or other pivoting means, which is retained in position by a nut 12 or otherwise. The pawl is centrally bored as at 13 to receive the bolt 11, and has 5 its four points 14 equally spaced therefrom, the space between the opposite pairs of points being cut away in a circular form to permit of one or the other of a pair of points to be applied to the ratchet teeth 8 10 to actuate the same in a right or left hand direction. The rear face of the pawl 10 is provided with a pair of seats arranged in a line with the central bore 13, and consists of sockets 15 bored to within a short distance 15 of the opposite face of the pawl in order to form a bottom wall to the said sockets. The adjacent face of the stock 1 is also provided with a pair of depressions 16 arranged in alinement with and at a distance 20 from the axis of the pivotal bolt 11, equal to the distance of the sockets 15 therefrom. A spring pressed pin 17, formed of non-wearing material, such as hard steel, is introduced into that one of the sockets 25 15 which is in alinement with the depressions 16, and has a spring 18, preferably of brass, located between the inner wall of the socket and the inner end of the pin 17 in order to normally exert a pressure upon the 30 pin toward the adjacent face of the stock 1 and to hold the outer end of the said pin, which is preferably rounded, into engagement with one or the other of the depressions 16 to maintain the one or the other of 35 that pair of points 14 adjacent the rotating head 3. The other pair of points 14 may be utilized as thumb pieces to manipulate the pawl and throw either the upper or lower point of the opposite pair into engagement with the ratchet teeth 8, in order 40 to secure a right or left hand movement of the rotating head 3 in applying or removing nuts.

It will be seen that when the pawl is arranged for one direction of movement, the pin 17 will have its seat in one of the depressions 16 and in the passage of the teeth 8 past that point in active position, in the retrograde movement of the stock 1, the pin 50 17 will ride slightly up the inclined wall of the depression 16 until the tooth has passed the active point of the pawl and under the influence of the spring 18 will have a tendency to ride down again until seated 55 in the deepest part of the depression 16, thus returning the active point into engagement with the teeth 8. Upon the reversal of the pawl by a manipulation of the operator, to bring the other point of that pair 60 into use for the opposite rotation of the head 3, the pin 17 will then find its seat in the other depression 16 (as indicated in Fig. 2) when the pawl may be maintained

in this position by the same means. By removing the bolt 11 the pawl may be completely reversed to bring the other pair of points into use, in the event of the first pair having become worn to such an extent as to not properly reach the teeth of the rotating head.

It will be seen that a wrench of extreme simplicity has been provided, consisting of few parts, and one that may not become readily deranged or broken, and furthermore that is readily applicable to nuts of 75 different sizes without the necessity of tedious adjustment of parts.

What is claimed is:—

1. The combination with a handle, and a head rotatably mounted on the handle and 80 having peripheral double teeth, of a pawl pivotally and rotatably mounted on the handle and having two pairs of points, an inwardly extending pair and an outwardly extending pair, and spring means for yieldingly holding the pawl in position to engage one of the inwardly extending pair of points with the teeth of said head, the outer pair of points being adapted for alternate engagement with the fingers to rock the pawl 85 and shift the inwardly extending pair of points for alternate engagement with the head, the pawl being adapted to be rotated to interchange the inner and outer pairs of points whereby to bring the finger engaging points into co-operative relation with the head when the inner points are broken and worn.

2. The combination with a handle, and a wrench head rotatably mounted on the 100 handle and having peripheral double ratchet teeth, of a pawl pivotally mounted on the handle and having oppositely extending pairs of spaced apart points, one pair extending inwardly toward the head for alternate engagement with said teeth to drive the head in opposite directions, and the other pair of points extending outwardly from the head for alternate engagement with the fingers to rock the pawl and shift said first 110 pair of points with respect to the head, the pawl being also mounted for rotation upon the handle whereby the pawl may be swung around to engage the outwardly extending pair of points against the head and turn 115 the inwardly extending points outwardly for engagement with the fingers.

In testimony, that we claim the foregoing as our own, we have hereto affixed our signatures in the presence of two witnesses.
